(57) **CLAIM**

The ornamental design for the set of shelf support members, as shown and described.

DESCRIPTION

The sole view of the set of shelf support members is a left front perspective view. The five members are, from the right top moving clockwise: a top cover piece, an intermediate cover piece, a bottom cover piece, a connector piece and a shelf support bracket. The right front perspective view is mirror image.

Some of the parts are shown broken away to indicate indeterminate length.
